UNITED STATES PATENT OFFICE.

WILLIAM N. SPRINGER, OF SOUTH BEND, INDIANA, ASSIGNOR TO AVERY COMPANY, A CORPORATION OF ILLINOIS.

PLOW.

1,332,079.

Specification of Letters Patent. Patented Feb. 24, 1920.

Application filed December 23, 1912, Serial No. 738,328. Renewed July 19, 1919. Serial No. 312,107.

To all whom it may concern:

Be it known that I, WILLIAM N. SPRINGER, a citizen of the United States, residing at South Bend, in the county of St. Joseph and 5 State of Indiana, have invented certain new and useful Improvements in Plows, of which the following is a specification, reference being had therein to the accompanying drawing.

10 The principal object of the invention is to provide in an engine gang plow in combination with the frame structure an improved arrangement of supporting wheels. Other objects will be apparent from the following 15 specification.

Of the drawing which illustrates the embodiment of my invention which I now prefer,

Figure 1 is a plan view. In this view 20 some of the plow parts are omitted and others indicated more or less diagrammatically.

Fig. 2 is a side elevation of the plow as shown in Fig. 1.

Fig. 3 is an enlarged detail view taken 25 partly in section along the line 3—3 of Fig. 1.

Referring to the drawings, it will be observed that the main frame of the plow comprises three principal elements, 1, 2 and 3. These frame elements are formed of structural steel parts preferably angle bars. The rear bar 1 is arranged diagonally at an angle of the line of draft, and as shown in the drawing, the vertical flange extends upward from the horizontal flange at the rear side thereof. The frame element 2 is at the front end and is arranged transversely at right angles to the line of draft. The frame element 2 is connected at one end with the 30 element 1 and is preferably arranged with the vertical flange extending upward from the horizontal flange from the front side thereof. The third frame element 3 is an angle bar arranged with its vertical flange extending downward from the horizontal flange at the inner side thereof. This element 3 is connected at its rear end to the rear part of the element 1 and extends forward from the point of connection along 35 lines parallel to the line of draft. Near its center the element 3 is bent and from the point of bending extends diagonally, parallel to the element 1, to a point of connection with the element 2 near the center thereof.

It will be noted that the element 3 is connected to the bottoms of the elements 1 and 2.

In addition to the three mentioned frame elements which have been described, I also provide supplemental bars or braces. In 60 the construction shown there are three such braces, these being indicated by 4, 5 and 6. The brace 4 is positioned at right angles to the frame element 1 and is connected at its rear end to the said frame element. At its 65 forward end it is connected to the frame element 2 near the outer end thereof. Intermediate its ends it is connected with the frame element 3. The braces 5 and 6 extend in generally transverse directions and 70 are connected at their ends to the frame elements 1 and 3.

The plow frame is supported on three ground wheels 7, 8 and 9. The wheel 7 is positioned in the angle between the elements 75 1 and 3 and is mounted upon a transverse shaft or axle 10. Bearings 11 and 12 are provided for this shaft 10, these bearings being secured respectively to the frame members 1 and 3. The wheel 8 is positioned 80 near the front end of the frame element 1 but at the rear side thereof. It is mounted on the shaft or axle 13 for which there are provided bearings 14 and 15. The bearing 14 is secured to a suitable longitudinal 85 bracket or angle bar 16 which is connected to the frame members 1 and 2. The bearing 15 may be secured directly to the frame element 1. Between the bearing 15 and the front frame element 1 I preferably provide 90 a reinforcing angle bar 17.

The third wheel 9 is secured to the frame element 2 at the outer end thereof in such a way that it can caster or swing about a vertical axis. As to the form of mounting for 95 this wheel 9 there can be variation, but the construction which I have shown has features of advantage. 18 is a pivot block which is rigidly secured by means of bolts to the end of the frame member 2. This 100 pivot block 18 has vertical pins or trunnions 19 and 20, the former being located at the top of the block and the latter being located at the bottom of the block and extending through a suitable aperture in the horizontal flange of the frame element 2. 21 is a block having a central bearing aperture for receiving the pin 19. A suitable nut and

washer on the pin holds the block in place. 22 is a similar block having a central bearing aperture to receive the pin 20. This bearing block is also held in place by a suitable nut and washer. 23, 23 are straps or bars bolted to the upper bearing block 21, and 24, 24 are similar straps or bars secured to the lower bearing block 22. These bars 23, 23, and 24, 24 extend backward and 10 downward and at their lower ends are provided with bearing apertures for the axle 25 upon which the wheel 9 is mounted. It will be observed that the construction which I have described provides a very rigid connection for the wheel 9, and, at the same time, permits it to swing freely about a vertical axis in advance of the horizontal axis of rotation.

As to the plowing devices which are connected with the main frame, there can be wide variation and my invention is not limited to any one form of plow body or connecting mechanism. In the drawings, however, for purposes of illustration I have 20 shown more or less diagrammatically plow bodies 26, 26 secured to beams 27, 27 which are connected to the frame for movement with respect thereto about normally fixed horizontal transverse axes. The pivot bearings are preferably formed in rearward extending brackets 28, 28 secured to the main frame element 1.

Preferably, though not necessarily, means are provided whereby the several plow bodies and beams can be lifted by means of power transmitted from one of the ground wheels, preferably 7. Such a power lifting mechanism is indicated more or less diagrammatically in the drawings, but it will 30 be such that it can be modified or omitted entirely without departing from the spirit of my invention. As illustrated, the power lifting mechanism comprises a diagonal shaft 29 mounted on the frame element 1. 35 On this shaft are cams 30 which engage rollers 31 on pivoted levers 32. These levers are connected by means of suitably guided chains 33 with levers 34 on the plow beams. These levers 34 are connected with ground 40 engaging wheels 35 in such a way that when the levers are swung forward by means of the chains, the wheels are forced downward with respect to the beams, the result being that the beams and plow bodies are lifted. 45 Power is transmitted to the shaft 29 from the transverse intermediate shaft 36 by means of gearing 37. The shaft 36 is driven from the ground wheel 7 and shaft 10 by means of the chain 38. The chain 38 is, of 50 course, constantly in motion when the plow is in operation and there is therefore provided, as indicated diagrammatically at 39, a clutch by means of which the shaft 36 can be temporarily connected to receive power. 55 When the clutch is engaged, power is trans-

mitted to rotate the shaft 29, and by means of the cams and other devices which have been described, the plows are lifted and held in lifted position. A subsequent engagement of the clutch will cause the further 70

rotation of the shaft 29 and cams 30 and permit the plows to be lowered. Preferably the cams 30 are so arranged on the shaft that the plows will be lifted and lowered successively, beginning at the forward end. 75

Draft is applied to the plow preferably by means of chains 40, 40, which are connected at their rear ends to the frame element 2 at 41, 41. 42 indicates diagrammatically a traction engine or other device for 80 pulling the plow.

It will be observed that the caster wheel 9 is located so that, during the normal operation of the plow, it is entirely within the main outlines of the frame. However, because of its position at the extreme outer end of the cantaliver part of frame element 2, it is possible for this caster wheel to swing outward and forward to any desired position without coming into contact with 90 any other parts of the plow. This construction not only enables the plow to respond very quickly and easily to the force of the draft during plowing, but also enables it to be turned very sharply while being transported from one point of use to another. The two wheels 7 and 8 are fixed against 95 bodily movement with respect to the frame and therefore by their engagement with the ground hold the frame against movement 100 105

100 bodily along transverse lines. The free mounting of the wheel 9, however, permits the frame as a whole to be easily swung about one or the other of the wheels 7 and 8 as a pivot. 105

I am aware that it has been heretofore proposed to provide an oscillatory wheel in combination with one or more fixed wheels in plows of the class in which one or both of the fixed wheels is adapted to travel in a furrow and below the normal surface of the ground. Plows of this class, however, are to be distinguished from engine gang plows of the class to which my invention relates. In an engine gang plow of the type herein described all of the wheels travel along the normal smooth surface of the ground and are not dependent upon the furrows for guidance.

What I claim is:

120 In an engine gang plow, the combination with the plowing devices, of a main frame having a rear main diagonal element to which the plowing devices are connected, a second diagonal element parallel to the 125 first and connected thereto and a front transverse element connected near its center to the forward end of the second diagonal element and at one end to the forward end of the first diagonal element, the other end pro- 130

jecting laterally as a cantaliver member and supporting wheels for the frame, one of the wheels being connected for oscillation about a vertical axis at the end of the said cantaliver member and directly in front of the said diagonal elements and the said plowing devices.

In testimony whereof I affix my signature in presence of two witnesses.

WILLIAM N. SPRINGER.
